VANITY CASE

Charles Dell'Elba, New York, N. Y.

Application September 17, 1940, Serial No. 357,088

1 Claim. (Cl. 240—6.45)

This invention relates to vanity cases and the like and has particular reference to a vanity case having a mirror and illuminating means for the latter.

One of the objects of the invention is to provide a vanity case of the type referred to in which the illuminating means are so disposed that glare will be avoided.

Another object is to provide a vanity case in which the light will diffuse over the mirror without the illuminating means itself being visible to the user.

Still a further object is to provide an electric lamp bulb which may be energized by suitable means, such as small batteries, and which lamp is so shielded that it will cause a diffused or indirect light to flood the mirror.

A further object is to provide a vanity case of the type indicated in which the electric light bulb is so arranged that it will illuminate the contents of the vanity case in addition to illuminating the mirror.

Other objects and advantages inherent in the invention will become apparent from the following specification when taken in conjunction with the accompanying drawing which shows a preferred embodiment thereof.

In the drawing:

Figure 1 is a perspective view of a vanity case according to the invention.

Figure 2 is a section taken along the line 2—2 of Figure 1.

Figure 3 is a section taken along the line 3—3 of Figure 1.

Figure 4 is a section taken along the line 4—4 of Figure 3, and,

Figure 5 is a section taken along the line 5—5 of Figure 3.

Referring in greater detail to the drawing, the vanity case comprises two hinged portions 10 and 11. Portion 10 may be selected for the cosmetic tray or receptacle portion, having recesses 12 and 13 for receiving the powder and rouge, respectively. It is obvious, of course, that additional recesses may be provided for additional cosmetic preparations.

The portion 11 may be used as the cover. The inner surface of the cover is mirrored in conventional manner so that it will constitute a reflecting surface or mirror.

The opposing sides of the cover portion 11 accommodate two battery housings 14 which may be removably inserted between the top and bottom wall members 19 and 20. The battery housings contain the batteries 15 and 15a on opposing sides. In order to balance the vanity case and because of the relative thinness of the cover portion 11, the battery housings 14 are convexed at 16. The receptacle portion 10 is provided with corresponding recesses 17 for accommodating these convexed portions when the vanity case is closed.

The battery housings are provided with supporting ridges 14a for the batteries.

The mirror 18 is framed within the side walls 19 and 20 and the perpendicular walls of the battery housings 14. Thus the mirror is countersunk between the frame constituted by these walls.

The lamp bulb 21 is supported in the perpendicular part of the wall 20 which latter wall will constitute the top when the vanity case is opened for use.

The wall 20 is also provided with a longitudinal shield 22 which extends across the lamp bulb. In this manner the light rays from the lamp will not shine in the eyes of the person using the invention. Furthermore, this shield diffuses the light over the mirror and produces an indirect lighting effect.

The perpendicular parts of the walls constituting the mirror frame may also be provided with reflecting surfaces in order to produce a greater flooding of the mirror. It might thus be stated that the mirror is set in a box of light. The mirror may be turned so as to reflect the light on the contents.

The two small batteries 15 and 15a provide the electric current for the lamp 21. One terminal is grounded in the metal vanity case by means of the spring retaining clip 23. The batteries 15 press against the spring contact clip 24 which is connected to one terminal of the lamp. The other terminal of the lamp presses against the spring contact clip 25 which contacts the circuit button 26. It will be understood that the circuit is completed by pressing down the contact clip 25 into contact with the batteries 15a.

A spring catch 27 is provided for holding the case in closed position. The batteries can easily be exchanged by removing the battery housings.

It will be understood that the invention is not limited to the exact disclosure herein described but may lend itself to a variety of expressions within the scope of the following claim.

What is claimed is:

45 A vanity case comprising a cosmetic receptacle and a cover having substantial depth hingedly interconnected along one edge, a mirror in the bottom of said cover, a frame defining the reflecting surface of said mirror, said frame having reflecting surfaces extending perpendicularly from said mirror, an electric light bulb depending from the perpendicular surface of said frame which is opposite said hinged edge, a solid opaque shield for said light bulb extending across said mirror, said shield being of such a depth that no direct light rays will interfere with the user's vision during the normal employment of the vanity case, and a pair of batteries oppositely mounted in said frame.

CHARLES DELL'ELBA.
